DESIGN FOR A WALL CASING FOR A DEODORANT DISPENSER OR SIMILAR ARTICLE

Frederic S. Grover, Rochester, N. Y., assignor to Rochester Germicide Company, Rochester, N. Y., a corporation of New York

Application September 30, 1938, Serial No. 80,160

Term of patent 14 years

To all whom it may concern:

Be it known that I, Frederic S. Grover, a citizen of the United States, residing at Rochester, in the county of Monroe and State of New York, have invented a new, original, and ornamental Design for a Wall Casing for a Deodorant Dispenser or Similar Article, of which the following is a specification, reference being had to the accompanying drawing, forming part thereof.

In the drawing:

Fig. 1 is a front elevation of a wall casing for a deodorant dispenser or similar article, showing my new design;

Fig. 2 is a bottom view thereof;
Fig. 3 is a top view thereof; and
Fig. 4 is a side view thereof.

I claim:

The ornamental design for a wall casing for a deodorant dispenser or similar article, as shown.

FREDERIC S. GROVER.
